Primary Examiner—Cathy Anne MacCormac(74) Attorney, Agent, or Firm—Howard C. Miskin, Esq.; Gloria Tsui-Yip(57) CLAIM

The ornamental design for a finger ring, as shown and described.

DESCRIPTION

FIG. 1 is a front elevational view of my new finger ring design, the rear elevational view being a mirror image thereof;

FIG. 2 is a top plan view thereof; the bottom, left and right side views are identical;

FIG. 3 is a front elevational view of a second embodiment of my new design, the rear elevational view being a mirror image thereof;

FIG. 4 is a top plan view thereof; the bottom, left and right side views are identical;

FIG. 5 is a front elevational view of a third embodiment of my new design, the rear elevational view being a mirror image thereof; and,

FIG. 6 is a top plan view thereof; the bottom, left and right side views are identical.

The darker shaded gemstones in FIGS. 1, 2, 5 and 6 illustrate gemstones of a contrasting color.
